UNITED STATES PATENT OFFICE

145,110

DESIGN FOR A SHOE

Clark L. Wilcox, Easton, Mass., assignor to Field and Flint Co., Brockton, Mass., a corporation of Massachusetts

Application March 5, 1946, Serial No. 127,110

Term of patent 14 years

(Cl. D7—7)

To all whom it may concern:

Be it known that I, Clark L. Wilcox, a citizen of the United States and a resident of Easton, county of Bristol, Commonwealth of Massachusetts, have invented a new, original, and ornamental Design for a Shoe, of which the following is a specification, reference being had to the accompanying drawing, forming part thereof.

In the drawing:

Fig. 1 is a top plan view of a shoe, showing my design;

Fig. 2 is a side elevation of the shoe; and

Fig. 3 is a side elevation of the shoe as viewed from the side opposite that shown by Fig. 2.

I claim:

The ornamental design for a shoe, substantially as shown.

CLARK L. WILCOX.
